LINDSLEY SCHEPMOES, OF HASBROUCK HEIGHTS, NEW JERSEY, ASSIGNOR TO THE SAFETY CAR HEATING & LIGHTING COMPANY, A CORPORATION OF NEW JERSEY.

ELECTRIC FIXTURE.

1,123,389.

Specification of Letters Patent.

Patented Jan. 5, 1915.

Application filed December 10, 1909. Serial No. 532,305.

To all whom it may concern:

Be it known that I, LINDSLEY SCHEPMOES, a citizen of the United States, residing in Hasbrouck Heights, county of Bergen, and 5 State of New Jersey, have invented new and useful Improvements in Electric Fixtures, of which the following is a description.

My invention pertains to that class of electric fixtures or lighting apparatus adapted to contain an electric lamp or bulb and direct the light therefrom in a desired manner and direction and protect the lamp or bulb from injury when it is desired to use the same in exposed places.

15 My invention has for its particular object to provide a fixture which may be used in railway cars adapted to be secured to the window panel alongside one of the seats or in case of sleeping cars in the corner formed 20 by the window panel and the usual berth partition.

A further object of my invention is to provide a fixture which will direct the light of a lamp in such manner that it will not 25 shine upon the occupant of the opposite seat where the seats are placed facing each other as in sleeping cars.

30 A further object is to provide a lamp of such form and construction that it may be fastened in place without necessitating cutting of the woodwork—that is, of such construction that the entire parts of the lamp or fixture shall be self-contained and adapted to be fastened flush against the usual 35 woodwork.

My invention is directed particularly to that class of fixtures in which it is desired 40 to use high efficiency bulbs such as metallic filament bulbs and on this account it is advantageous that the bulb should always be held with the filaments in a vertical position and that the switch or key used for turning the lamp on and off should not subject the lamp to sudden shocks or vibrations 45 which would tend to break the filaments.

In the drawing Figure 1 represents an elevation of my improved fixture as designed for use in a corner as, for example, a corner formed by the window panel and the 50 berth partition of an ordinary sleeping car to which the same is shown applied. Fig. 2 is a vertical section of my improved fixture in a plane midway between the two walls forming the corner shown in Fig. 1.

In the drawing 1 represents the walls or 55 partitions to which my fixture is applied.

2 represents a back casting or frame secured to the walls as by the screws 3. This casting or back plate is provided with an extension 4 adapted to receive and hold in 60 place the switch 5 and has fitted thereto the front or removable portion 6 which carries the prismatic globe or bowl 7. The removable portion 6 is provided with a flange or extension 8 having two small gibs or hooks 65 9 adapted to pass through the opening 10 in the member 2 and engage the member as plainly shown in Fig. 2 in such manner that the screw 11 when made up into the top of the member 2 will hold the member 6 firmly 70 in place. The bowl 7 is passed through the opening in the flanged portion 12 of the member 6 and is provided with a flange engaging the same as indicated. The bowl 7 is firmly held in place by a metallic ring 13 75 which is passed under a couple of pins, one of which is indicated at 14 and then caught at another point by the screw 15 carried by the lug or boss 16.

17 is a web member carried by the member 2 and having attached thereto a spring clip 18 so shaped as to firmly grip the socket 19 and attached to the member 17 as by screws 20. The socket 19 thus firmly held between the jaws of the spring clamp 18 is 85 adapted to hold the bulb 21 in its proper position within the fixture.

22 represents a reflector adapted to direct the back rays of the lamp so that they will 90 pass in a desired direction through the prismatic bowl 7. The reflector 22 is carried by the member 17 and attached thereto as by screws 23.

24 represents a wire cleat carried by the member 17 and adapted to hold the wires 95 25 in place, the said wires being connected with any suitable source of current and with the lamp 21 through the switch 5.

26 represents apertures in the member 2 for the purpose of properly ventilating the 100 fixture.

To place my fixture in use I proceed as follows: I first fasten the back plate 2 in place upon the walls 1 as by means of the screws 3, the proper wires having been led 105 to the proper location in the panels. I then connect the wires with the switch 5 and the socket 19 and then press the socket in

place between the jaws of the spring clip 18. I then insert the bulb 21 in the ordinary manner and then place the bowl 7 in the front piece 6 as shown in Fig. 2, 5 then place the ring 13 under the pins 14 and put in the screw 15 and tighten the same so as to bring the proper pressure upon the flange of the bowl 7. I then insert the hooks 9 into the opening 10 until they en- 10 gage the back of the member 2. I then swing the upper part of the piece 6 into nearly a vertical position and lift the same slightly to allow the screw 11 to clear the member 2 until the said screw engages its 15 threaded aperture in the member 2. I then make up the screw 11 which presses the member 6 into the position shown in Fig. 2 and holds the same firmly in place. If 20 the wires 25 are connected to the proper source of current manipulation of the switch 5 will then turn the light on or off and a snap movement may be used in the switch without subjecting the filaments of the lamp 21 to any severe vibration owing largely to 25 the flexible manner in which the lamp is held. If desired to remove the bulb the screw 11 may be backed out and the front piece 6 swung away from the member 2 and lifted so that the members 9 will dis- 30 engage the back member 2 and then the piece 6 removed. Then the bulb may readily be removed or the socket taken from its spring clip 18 if desired to permit of any examination of wiring, etc.

35 In practice I prefer to make the bowl 7 of such prismatic character that the refraction of the same will tend to concentrate the light given by the bulb 21 into a conical shaped beam directed approximately 45 degrees below the horizontal and 45 degrees in the lateral direction from each of the corner walls 1. When so directed the light in use in one corner of a section of a sleeper will be useful to the occupant of the adjacent seat and not annoying to the occupant of the seat opposite which is a great practical advantage.

From the foregoing it will be plain that I have produced a fixture which may be applied to the corner formed by the window panel and the berth partition in the ordinary sleeping car without cutting away of the panel or partition to make clearance for portions of the fixture. Further that I have produced a compact form of fixture which will cause the rays of the bulb or lamp contained therein to be directed in such manner as to be practically more useful than the ordinary exposed lamp used for 60 this purpose. Also that I have provided a fixture which may be readily opened and cleaned and in which the parts needing renewal or repair are easily accessible and may be readily replaced and that my fixture 65 has self-contained therein a switch in such

position and so mounted that it will not be heated to any appreciable extent by the heat given out by the lamp and will not in its operation subject the filaments of the bulb to severe vibration.

I do not wish in any way to limit myself to the exact details of construction shown in the accompanying drawing as it will be obvious that considerable changes may be made in the design of my fixture without departing from the scope of the invention which is as set forth in the following claims:

1. An electric fixture having, in combination, an angular back-plate of a form adapting it to be secured in a corner or angle, and formed at its lower end into a receptacle for a switch mechanism, and above said receptacle into a support for a lamp; a bowl-carrier partially closing the front of said plate; and means for supporting the bowl-carrier at the top of said back-plate, substantially as described.

2. An electric fixture comprehending an angular back-plate of a form adapting it to be secured in a corner or angle; means at the lower end of said plate for supporting an electric switch; said plate between its ends being formed into a web-member and having means for supporting an electric socket; a bowl-carrier member and supporting means therefor at the top of the plate; and coöperating means for supporting said bowl carried by said plate above the switch supporting means.

3. An electric fixture comprehending an angular back-plate of a form adapting it to be secured in a corner or angle, an electric switch carried by the lower portion of said back-plate, a pair of flexible jaws carried by said back-plate within the angle thereof, a lamp socket held in position by said jaws, and flexible connection between the switch and said socket, whereby vibration caused by operation of the switch is not transmitted to the said socket.

4. An electric fixture having, in combination, an angular back-plate of a form adapting it to be secured in a corner or angle; means projecting from said back-plate within the angle thereof for supporting a lamp-bulb; a bowl-carrier supported by said back-plate at its top and extending from side-to-side thereof and to near its longitudinal center so as to cover the bulb-supporting means; said bowl-carrier being formed into a bowl supporting ring and below the latter into a switch-receiving extension.

5. An electric fixture having, in combination, an angular back-plate of a form adapting it to be secured in a corner or angle, the lower portion of said back-plate being reduced, a switch located in said reduced lower portion, means for supporting an electric lamp carried by the back-plate above the switch, a bowl-carrier supported by the back-

plate above the switch and partially closing the front of the back-plate, means for securing the bowl-carrier to the plate, and a transparent bowl secured to the carrier and the 5 plate at an angle to the carrier.

6. An electric fixture having, in combination, an angular back-plate adapting it to be secured in a corner or angle, a switch carried by the lower portion of the back-plate, 10 an electric lamp mounted in the upper portion of the back-plate, a bowl-carrier for

partially closing the front of the back-plate, said bowl-carrier having hooks at its lower end to engage the back-plate to hold the carrier in position, and fastening means to secure the carrier to the back-plate at its upper end, and a transparent bowl mounted on the carrier in proximity to the lamp. 15
